M. McDONALD

CARD INDEX AND FILE

Filed April 15, 1926

UNITED STATES PATENT OFFICE.

MALCOLM McDONALD, OF ORENCO, OREGON, ASSIGNOR TO FLORENCE McDONALD, OF ORENCO, OREGON.

CARD INDEX AND FILE.

Application filed April 15, 1926. Serial No. 102,193.

The object of my invention is to provide a new and improved card index and file wherein, when the cards are filed within the holder a space will be left exposed at the top of the card upon which the name to be indexed upon the card will be exposed to view and unobstructed when the cards are in normal position of use.

A further object of my new and improved card index and file, is to provide a card holder that will engage the card at its lower extremity and will hold the same in fixed position with relation to the holder.

A further object of my invention is to provide a stirrup; the object of which is to permit the hinging of one or more cards about the stirrups to facilitate the inspection of the card under observation.

A still further object of my invention is to provide a longitudinal guideway upon which the stirrups may be assembled and along which the stirrups may be made to pass, the width of the stirrup determining the spaced relationship that is to be maintained between the lower edges of the cards and the space that will remain exposed along the top edge of the card upon which the name is to be printed.

A still further object of my invention is to provide a holder for cards that will permit of the filing of cards of different lengths in the same file without in any way interfering with the efficiency of the same.

A still additional object of my invention consists in providing holders for the cards, wherein the cards may be easily placed within the card holder, and wherein the card may be held intermediate its ends along one side, thus developing the full strength of the card.

Additional objects consist in the forming of a holder or tray that may be easily assembled within a tray or holder that will fit into a cabinet in which several of said trays of uniform size may be locked into position within the cabinet to prevent loss or inspection of the cards.

With these and incidental objects in view, the invention consists in certain novel features of construction and combination of parts, the essential elements of which are set forth in the appended claims and a preferred form of embodiment of which is hereinafter shown with reference to the drawings

which accompany and form a part of this specification.

In the drawings:—

Fig. 1 is a perspective view of a cabinet into which a series of the card holders may be placed for safe-keeping when not in use. 60

Fig. 2 is a plan view of a preferred embodiment of a holder wherein cards may be placed in series, with a plurality of series of cards in parallel alignment. 65

Fig. 3 is a fragmentary detached view of 65 a card in place within the card holder, and the card holder being in place within the stirrup and in hinged relationship therewith, the stirrup being in place upon the longitudinal guideway. 70

Fig. 4 is an end view taken on line 4—4 of Fig. 3, looking in the direction indicated.

Fig. 5 is a front elevation of the card shown removed from the card holder.

Fig. 6 is a front view of a preferred form 75 of the card holder shown removed from the stirrup.

Fig. 7 is an edge view of the card series taken on line 7—7 of Fig. 2, looking in the direction indicated. 80

Like reference characters refer to like parts throughout the several views.

In the drawings 1 is a card tray, preferably made of a bottom sheet of rigid material, having a front upturned end 2, and having a pull 3, disposed upon the exterior wall thereof. A rear end wall 4, is disposed upon the opposite end to that of the front wall and downturned side flanges 4¹ may be formed on the bottom to give a greater rigidity to 85 the tray. The side flanges further provide for a spaced relationship to be existent between the bottom of the tray and the tray support. An inclined surface 5, may be provided in the bottom of the tray and at the 90 rear of each series of cards to be placed within the tray, the object of which is to elevate the free end of the rearmost cards to maintain a uniform height of the cards when the series has been completed in each 95 line of cards. Guideway strips 6 running lengthwise of the tray section are formed by cutting out portions of the bottom at each side of the strip, and stirrups 7 are maintained thereupon and in slideable relationship therewith. Stirrups 7 are made in the form of an elongated U having 100 upturned end portions 8 and 9 which have

central holes 10 disposed therein through which the card holders 11 are maintained in hinged relation therewith.

- The card holder 11 is preferably made of 5 one piece and is so formed of suitable material as to cause the edge portions 12 and 13 to meet along their inner transverse surfaces in order that the card 14 may be placed therebetween and be gripped therebetween. 10 The outer edges of the same are outturned to permit of ease in the entrance of the card between the surfaces. Projections or lugs 15 are formed at either side of the card holder 11 to permit of engagement into the holes 10 15 of the stirrups and cause a hinged relation to be maintained between the stirrup 7 and the card holder or clip. The card holder may be formed about a shaft having projecting ends or the same may be formed of one piece of 20 sheet stock having projecting bearings formed thereupon as illustrated at 15. A preferred form of card holder is that illustrated in Fig. 6 wherein the card holder is formed of a single piece of sheet stock and 25 wherein the projections 17 are so formed as to permit the upturned ends of the stirrups to be permitted to pass into the slots or openings 18 and to be snapped into position about the projections 17 which will form a completed article of manufacture wherein dislodgment of one part from the other will not be so likely to occur. In the forming of the 30 cards it has been found desirable to form notches or indentations 19 in the lower edges 35 of the cards to permit of the seating of the cards to the full depth within the card holder, the upturned ends of the stirrups fitting into the notches 19 thus formed in the cards. With the notches so formed within 40 the lower edge of the cards, I have found the cards have a tendency, especially in the layer cards, through continued use, to tear at, or beginning with the notch thus formed. To overcome this tendency of premature de- 45 struction, through the creation of the notches 19 in the lower edge of the card holder, I have formed ends upon the card holder, as shown in Fig. 6 at 20, wherein the card holder engages and clamps the card beyond 50 the notches 19 formed therein. This form of construction I have found, through continued use, prevents the premature destruction of the card due to tearing due to the notches being formed and also permits of 55 the seating of the card to the full depth within the card holder. I have formed a locking hole 21 at the rear of the bottom of the card tray through which a locking bar may be passed to prevent the removal of the card 60 tray from the cabinet.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. The combination in a card index and file of a card tray formed of metal and comprising a guideway strip formed as a part of the bottom of said tray; stirrups carried by said strip; a card holder hingeably secured to each stirrup, said card holder being formed of a single piece of metal folded upon itself to form two engaging surfaces and provided with means at each end of the fold to hingeably engage said stirrup, and 70 an index card provided with parallel recesses along one edge thereof, said recesses each to pass about one end of said stirrup when the edge of the card between said recesses is inserted in said holder. 80

2. The combination in a card index and file, of a card tray formed of metal having upturned ends and downturned side flanges, and comprising a plurality of guideway strips formed as a part of the bottom of 90 said tray; an inclined portion formed at the rear of each strip; stirrups carried by each strip, said stirrups comprising a metal strip having upturned ends, there being a hole formed through each end; a clip composed 95 of a single piece of metal folded upon itself and having outstanding lugs formed in alignment with said fold, said lugs engaging the hole in each upturned end of said stirrup; an index card provided with spaced 100 parallel notches formed in its lower edge, that portion of said index card between said notches to fit within said clip, and said notches to fit about the upturned edges of 105 said stirrup.

3. The combination in a card index and file of a card tray formed of metal and having upturned ends and downturned side flanges, and comprising strips formed as a part of the bottom of said tray, said strips 110 being formed by cutting away a portion of the bottom of the tray at each side thereof; stirrups freely carried upon said strips; said stirrups being formed with upturned ends provided with bearing holes therethrough; 115 and clips provided with outstanding lugs to engage the holes in the upstanding ends of said stirrups.

4. The combination in a card index and file of a card tray formed of metal and having ends and side walls, and having one or more guideway strips formed as a part of the base of said tray; stirrups carried upon each strip and in slidable relation therewith, card holders disposed within the stirrups and in hinged relation therewith, said card holders each formed of one piece bent about its longitudinal medial line to form clamping surfaces with out-turned edges, 120 an index card provided therefor, said index 125

card adapted to be seated to the full depth of said card holder and an inclined member secured upon the base of the card tray at the rear thereof, adapted to have the free end of an index card rest thereupon.

5. The combination in a card index and file of a guide strip, U-shaped stirrups slid-

ably carried upon said guide strip, card holders having clamping surfaces disposed within the stirrups and in hinged relation therewith, and cards disposed between clamping surfaces of the card holders and removable therefrom.

MALCOLM McDONALD.
